STOKER PIPE

Harold T. Blum, Glenmont, Ohio, assignor to
Briar Hill Corporation, Millersburg, Ohio, a corporation of Ohio

Application July 28, 1939, Serial No. 287,144

2 Claims. (Cl. 131—181)

The present invention is an improvement in smoking pipes and more particularly relates to smoking pipes provided with a mechanism for controlling the firing of the tobacco therein.

5 The principal object of the present invention is to provide a mechanism for controlling the firing of the tobacco within a pipe bowl and which mechanism can be very quickly and easily mounted within the pipe bowl for its intended purpose and yet can be as readily removed from the bowl.

10 Another object of the present invention is to provide a stoking mechanism for smoking pipes of the conventional type, that is, a pipe having a bowl and stem connected to and extending substantially at a right angle away from said bowl, which does not take but a small proportion of the space within the pipe bowl and, at the same time, does not materially alter the appearance of the conventional pipe.

15 20 A still further object of the present invention is to provide a smoking pipe wherein tobacco can be consumed and the smoke drawn therefrom without passing through the main body of the unburnt portion of the tobacco and in which the level of the burning portion of the tobacco can be maintained at varying levels relative to the top of the pipe bowl as desired.

25 Another important object of the present invention is to provide a smoking pipe having a tobacco stoking mechanism incorporated therein and which mechanism, while economical to manufacture, can be removed from or mounted within the pipe with a minimum number of motions and without the use of tools.

30 35 In the following detailed description of the accompanying drawings, further objects of the present invention will be in part pointed out and in part obvious from a consideration thereof.

40 45 In order that the invention and its mode of operation may be readily understood by persons skilled in the art, I have in the accompanying drawings and in the detailed following description based thereupon, set out embodiments of the same.

45 In the drawings:

Fig. 1 is a cross sectional view of a smoking pipe having a tobacco stoking unit incorporated therein and which unit is shown in a side elevation thereof.

50 55 Fig. 2 is an enlarged detail view taken on line 2—2 of Fig. 1.

Fig. 3 is an enlarged detail view of a portion of the smoking pipe taken on line 3—3 of Fig. 1.

Fig. 4 is an enlarged side cross sectional detail view of a portion of the smoking pipe showing the

mounting of the tobacco stoking unit therein and is taken on line 4—4 of Fig. 2.

Fig. 5 is a top elevation of a base bearing and retaining member comprising an element of the present invention.

Fig. 6 is a side cross sectional view taken on line 6—6 of Fig. 5.

Fig. 7 is a side cross sectional view of a smoking pipe and showing a modified form of the tobacco stoking mechanism mounted therein and shown 16 in side elevation.

Fig. 8 is an enlarged top cross sectional detail view taken on line 8—8 of Fig. 7.

Fig. 9 is a partial side cross sectional detail view taken on line 9—9 of Fig. 8 and showing a 15 smoke passage.

Fig. 10 is an enlarged side cross sectional detail view of a second modification of the present invention.

Fig. 11 is a top cross sectional detail view taken 20 on line 11—11 of Fig. 10 and showing a retaining ring in position.

Fig. 12 is an enlarged side cross sectional view of the control and elevating member forming an element of the tobacco stoking unit, and

Fig. 13 is a side elevation of an elevating rod.

Referring now more particularly to the accompanying drawings wherein like and corresponding elements are designated by similar reference characters, numeral 1 designates a conventional 30 type of smoking pipe having a pipe bowl 2 and a stem 3 connected to and extending substantially at right angles from the base end of bowl 2, said stem 3 having a mouthpiece 4 connected thereto.

Bowl 2 has an internal chamber 5, to the lower 35 end of which is connected a bore 6 of stem 3 and which bore 6 is connected to bore 7 of the mouthpiece.

Chamber 5 has a pair of longitudinally and diametrically opposed slots 8 formed in its side 40 wall. The base of bowl 2 has a circular opening 9 formed therethrough and in which opening 9 is positioned the bearing portion of a tubular bearing and retaining member 10. In order to retain member 10 within said opening 9, the same may 45 be cemented to the walls thereof, but it is preferable to flare the lower end 11 of the member 10 outwardly for encompassing opening 9 on the outer side of the bowl 2. The opposite end of member 10 has an annular flange 12 formed extending outwardly therefrom and which flange 12 is seated upon the lower interior face of bowl 2. A plurality of resilient fingers 13 are formed extending from the outer edge of flange 12 and which fingers 13, which have outwardly curving 50

55

upper portions, form an annular recess with flange 12 at their lower portion.

A tubular controlled member 14, having threads 15 formed extending from the upper portion of the bore thereof, is seated within and through the bore of member 10 and is retained in this position by fingers 13 contacting an annular flange 16 formed extending from tubular member 14. Further, member 14 is provided with openings 17 formed through the wall thereof, whereby oil can be presented to the bore of member 10.

A rod 18, having threads formed upon its periphery, is positioned within the bore of tubular member 14 and in threaded engagement with threads 15 of said bore. The lower end of said rod 18 has a blank projecting portion 19 which limits the upward movement of the rod 18 within the bore of member 14.

20 The opposite end of rod 18 has a rectangularly-shaped head 20 which extends through a similarly shaped and centrally located opening formed through a tobacco-supporting disc 21 and said head 20 is flattened, whereby, disc 21 is fixedly connected to the upper end of rod 18.

Disc 21 has an annular series of openings 22 formed therethrough and which openings are positioned near the outer edge of disc 21 for a specific purpose which is more fully explained 30 hereinafter. The diameter of disc 21 is substantially equivalent to the diameter of chamber 5, whereby, the periphery of disc 21 slidably engages the periphery of chamber 5. Said disc 21 further has a pair of diametrically opposed keys 35 23 which extend within slots 8 and prevent the rotation of disc 21 laterally of chamber 5 but, at the same time, guide said disc 21 in its longitudinal movement upwardly and downwardly within said chamber 5.

40 Figs. 7 to 8 inclusive, disclose a modified arrangement of the previous disclosed device, wherein openings 22 of said disc 21 are not required. In the present modification, rod 18 has mounted upon the head 20 thereof a disc 24 which is of a slightly smaller diameter than the 45 diameter of the chamber 5 and is spaced from the wall of said chamber. A passageway for smoke between the periphery of disc 24 and the wall of chamber 5 is thereby provided. This opening 26, 50 as shown in the drawings, is greatly exaggerated in width for the purpose of clearness and preferably would have a width of approximately $\frac{3}{16}$ ", or thereabout. Disc 24 also has a pair of diametrically opposed keys 25 which fit within and 55 slide longitudinally of slots 8 formed in the wall of chamber 5, thereby preventing the rotation of disc 24 and its fixedly connected rod 18.

Any pipe bowl may readily have an opening 9 formed through the base thereof and a pair of 60 longitudinally extending slots 8 formed in the wall of the bowl chamber. With these slight modifications, the present tobacco stoking unit can be quickly mounted therein by inserting the bearing portion of member 10 within opening 9 65 and fixedly connecting the same to the walls of said opening by interpositioning a cement or adhesive therebetween. Preferably, however, end 11 of member 10 can be flared outwardly and this flared end 11, in combination with annular 70 flange 12, prevents member 10 from moving longitudinally of opening 9. With said member 10 thus positioned, tubular member 14 can be inserted within the open end of the chamber 5 and inserted within the bore of member 10. As flange 75 16 of member 14 contacts the upper end of resi-

lent fingers 13, it will gradually force the fingers 13 outwardly, thereby permitting its entrance within the fingers 13 until contacting the upper face of flange 12, at which time the fingers 13 will snap back into their normal position and 5 retain the member 14 in such a manner as to prevent any possible longitudinal movement thereof relative to the bore of member 10. However, member 14 can rotate within the bore of member 10 as can flange 16 within the fingers 13. 10

Before said tubular member 14 has been inserted within the bore of member 10, threaded rod 18 is inserted within the open end of the bore thereof and threadedly engages threads 15 thereof, whereby rod 18 can be screwed inwardly 15 and outwardly of the bore of member 14. Thereupon, disc 21 is fixedly mounted upon head 20, thereby limiting the inward movement of rod 18. The upward or outward movement of rod 18 is limited by stop 19 engaging with the face of the 20 threads 15 and said stop 19 being formed having a blank periphery, it cannot pass through said threads 15. Members 14, 18 and disc 21 are preferably formed from a lightweight metal, as for example aluminum, while member 10 is formed 25 from a resilient metal such as steel, or may comprise spring steel fingers 13 mounted upon a lower portion of a suitable bearing metal.

In the operation of the present device, tobacco is placed within the chamber 5 and supported 30 upon disc 21. Upon a flame being applied to the tobacco and a draft created by drawing through mouthpiece 4, the tobacco will become ignited. Depending upon the particular taste of the user of the smoking pipe, the burning portion 35 of the tobacco can be maintained at various levels within the chamber 5 and the supporting disc 21 drawn away from the bottom portion thereof after each advancement. To maintain this tobacco as desired, the portion of tubular member 40 14 extending outwardly from bowl 2 is grasped by the smoker and given a righthand rotation, whereby, threaded rod 18, due to its threaded engagement with member 14, will be caused to unscrew therefrom, since keys 23 operating in 45 slots 8 do not permit the rotation of rod 18 with member 14. The unscrewing of rod 18 advances disc 21 upwardly until the burning portion of the tobacco reaches the desired level. At this time, tubular member 14 is given a lefthand rotation, 50 returning rod 18 therein and drawing disc 21 downwardly from the bottom portion of the tobacco. Openings 22, being positioned close to the walls of chamber 5, will draw the smoke from the burning portion of the tobacco downwardly 55 between the wall of chamber 5 and the peripheral portion of the tobacco and not through the main body of the tobacco. Said smoke contacting the wall of chamber 5 will be relatively cooled and 60 moistures, heavy oils and tars condensed therefrom. After said smoke has passed through openings 22, it will be conducted through the lower portion of chamber 5 and bore 6, all of which are maintained relatively cool due to the protection of the tobacco upon the disc 21, as 65 well as the disc 21 itself. Upon the smoke contacting the lower portion of chamber 5 and the metallic elements of the stoker unit, it will be relatively cooled to an extent sufficient to cause the condensation of further moisture, oils and 70 tars therefrom, whereby a comparatively cool, dry and tar-free smoke issues from mouthpiece 4.

In the arrangement shown in Figs. 7 to 9 inclusive of the drawings, tobacco is placed upon disc 24 and within chamber 5 and said disc 24 75

is automatically raised and lowered in a manner similar to that described for the manipulation of disc 21. However, the smoke from the burning portion of the tobacco is drawn downwardly along the walls of chamber 5 due to the sucking of the smoke past the periphery of disc 24, that is, through passageway 26. By providing passageway 26 adjacent to the walls of chamber 5 at all times, the smoke from the burning portion must necessarily contact said wall and the mo-
5 tures, heavy oils and tars will be condensed from the smoke due to the cooling thereof upon con-
10 tacting the relatively cooler surface of the walls. The smoke, after passing through chamber 26,
15 is drawn through the lower portion of chamber 5, thence to bores 6 and 7 to the mouthpiece of the pipe and during this passage, it contacts the relatively cooler surfaces of said bores, said chamber and also the metallic elements of the
20 stoking mechanism, whereby the smoke is fur-
ther cooled and the heavy oils, moisture and tars are condensed therefrom. The elements com-
prising the stoker mechanism have exceptionally
25 good heat-conductive qualities for drawing the heat away from the lower portion of chamber 5 and, at the same time, add no noticeable weight to the smoking pipe.

In Figs. 10 to 13 inclusive, is disclosed a second modification of the stoker unit, which unit is mounted, as in the previous forms of the invention, within the bowl 2 of a smoking pipe 1, which bowl has an opening 9 formed through the base thereof and a pair of diametrically op-
30 posed and longitudinally extending slots 8. A bearing 33 is mounted within opening 9 and cemented thereto. A tubular control and elevating member 27 is rotatably mounted within and ex-
35 tends through the bore of bearing 33 and has annular flange 29 seated upon and slidably con-
40 tacting annular flange 34 of the bearing 33.

Member 27 has an annular recess 28 formed in the lower portion of the periphery thereof in which a three-quarter resilient ring 32 is inserted. The ring 32 extends from within slot 28 and slid-
45 ably contacts the lower edge of bearing 33 and thereby cooperates with flange 29 to prevent the longitudinal movement of member 27 within the bore of bearing 33 and, at the same time, per-
50 mits the lateral rotation of member 27 within said bearing. As in the previous modification, an elevating rod 18 having a threaded periphery is inserted within the bore of member 27 and threadedly engages openings 31 extending from the upper portion of said bore. The head 20 of member 18 has either a disc similar to disc 21 or disc 24 mounted thereon and fixedly connected thereto. Members 27, 18 and 21 or 24 are pref-
55 erably formed of a lightweight metal and bearing 33 may be formed from a similar material or
60 any suitable bearing material.

To operate a smoking pipe having this modified form of the stoker mechanism mounted therein, it is necessary to position tobacco within the chamber 5 and upon the tobacco supporting

disc. By grasping the lower end of member 27, that is, the portion extending from within the bowl 2, the same can be given a righthand rotation and threaded rod 18 will be unscrewed from the threads 31, thereby elevating the tobacco 5 supporting disc. Upon member 18 receiving a left-
10 hand rotation, rod 18 will be returned within the bore of member 27 until the tobacco supporting disc contacts the upper end of member 27 and prevents the further inward movement of rod 18. 10

When it is desirable to cleanse the interior of the smoking pipe 1, ring 32 can be pulled away from member 27 and due to the resilient qualities of the ring, it will be gradually spread apart at the open end thereof so that the same may be 15 readily removed. Upon the removal of ring 32, member 27, rod 18 and the tobacco-supporting disc can be moved outwardly through bowl 2, whereby the interior of the same is cleared for being brushed and boiled, or otherwise treated 20 for cleansing the same. A reversal of the fore-
going, that is, member 27 and its accompanying elements 18 and the tobacco-supporting disc can be inserted within chamber 5 and member 27 through the bore of bearing 33 until stopped by 25 flange 29 contacting flange 34, at which time ring 32 can be forced into recess 28 and during this insertion, the ends of ring 32 will be forced apart by member 27 until they pass the thickest part of member 27, at which time the ring will 30 snap back to its normal shape, thereby locking member 27 longitudinally of the bearing 33.

The present invention is capable of consider-
able modification but any such modifications thereof as come within the scope of the accom- 35 panying claims are deemed to be a part of the present invention.

I claim:

1. An improvement in smoking pipes comprising a pipe bowl having an opening formed through the base thereof, a stem connected to said bowl, a tubular member mounted in said opening, rotatable means for progressively rais-
40 ing and lowering tobacco within said bowl being rotatably mounted through the bore of said tubu-
45 lar member, a projection extending from the outer surface of said rotatable means and re-
silient fingers connected to said tubular mem-
ber and capable of receiving said projection there-
50 for retaining said rotatable means lon-
gitudinally of the bore of said tubular member.

2. An improvement in smoking pipes comprising a pipe bowl having an opening formed through the base thereof, a stem connected to said bowl, a tubular member mounted within said opening, said tubular member having an annular series of resilient fingers formed at the upper portion thereof, means for raising and lowering tobacco within said bowl rotatably mounted with-
55 in said tubular member, a projection formed upon the periphery of said rotatable means and en-
compassed by said fingers.

HAROLD T. BLUM.
